OPHTHALMIC PAD AND METHOD OF MANUFACTURING SAME

Henry J. Langknecht, Rochester, N. Y., assignor
to Shuron Optical Company, Inc., Geneva,
N. Y., a Corporation of New York

Application April 6, 1931. Serial No. 528,133

9 Claims. (Cl. 88—48)

This invention relates to a new and improved ophthalmic pad and method of manufacturing the same.

The main object is to provide a pad which may be manufactured speedily and economically, and the different parts of which may be assembled together in a ready and easy manner, and which will remain securely locked together after the assembling operation.

10 More specifically, the invention contemplates a novel securing of a journal bearing to a pad consisting essentially of a single piece of material such as zylonite, celluloid, mother of pearl, ivory, etc.

15 Other objects and advantages relate to the details of the manufacturing method and the resultant article all as will more fully appear from the following description taken in connection with the accompanying drawing in which:

20 Figure 1 is a perspective view of a spectacle frame embodying my invention.

Figure 2 is a perspective view of one side of my improved pad.

25 Figure 3 is a perspective view of the metal insert for the pad.

Figure 4 is a section on line 4—4 of Figure 3.

Figure 5 is a section on line 5—5 of Figure 3.

30 Figure 6 is a sectional longitudinal view of two parts of the pad before assembling, and with the assembling die in position.

Figure 7 is a longitudinal sectional view through the completed pad.

35 Figure 8 is a plan view of the rear face of the pad showing how the same is secured to the spectacle frame.

40 The pad 1 is adapted to be used with a spectacle frame having the usual rims 2, temples 3, and bridge 4, and may, as stated, be made of celluloid, zylonite, mother of pearl or any other suitable non-metallic material.

45 Although a pad embodying my invention may be made in various shapes and forms, I prefer to have the pad 1 approximately elliptical in shape with one face rounded, as shown at —a— on Figure 6, and with the other face flat, as shown at —b— on Figure 6.

50 I provide in the flat face —b— of the pad 1, a centrally disposed recess 5, which I prefer to have follow the contour of the pad 1 in general shape.

55 The base of the recess 5 is preferably flat and the side walls thereof are inclined upwardly and inwardly towards the side —b— so that the area of the flat bottom of the recess 5 is greater

than the area of the open end of the recess 5 and the side walls overhang the base.

So that the metal insert for the pad 1, about to be described, may be more securely locked in position and prevented from turning after it is assembled, I prefer to have the recess 5 oval in shape, although other out-of-round forms may be used.

For the purpose of providing a convenient and positive means for attaching the pad 1 to a spectacle frame, I provide a member 6 of ductile metal having a journal bearing portion 7 made integral with or rigidly secured to a base 8. The base 8, when in a flat condition, conforms substantially in size and shape to the flat bottom of the recess 5.

The method used by me in assembling the member 6 with the pad 1 is as follows. The bottom portion 8 of member 6 is shaped, pressed or otherwise formed substantially saucer shape or concavo-convex, as indicated in dotted lines, Figures 4 and 5. When in this form, the over-all area of the part 8 is reduced sufficiently so that the part 8 may be inserted through the opening into the recess 5. The pad 1 is placed in position on a suitable support 9 indicated in dotted lines on Figure 6. The tubular portion 7 of member 6 is inserted in a recess 10 and in a die 11, and the dished portion 8 of member 6 is inserted into recess 5, and the die 11 is then moved downwardly to force the part 8 to the bottom of the recess 5 and the downward movement of the die 11 is continued to flatten out the part 8 so that the same will rest on the flat bottom of the recess 5 with its edge underneath the overhanging side wall of the recess. This flattening of the part 8, as described, will increase its over-all area so that it will be impossible to remove the same through the opening leading to the recess 5, and the member 6 and the pad 1 are thus 65 70 75 80 85 90 95 100 105 110

locked securely together.

In Figure 6, the member 6 is shown as about to be inserted into the recess 5, and in Figure 7, the member 6 is illustrated in position in recess 5 with the part 8 flattened out to rest on the bottom of the recess 5.

For the purpose of improving the appearance of the pad 1, and for the purpose of covering the part 8 so that the pad 1 may be more easily cleaned, I prefer to place on the outer surface of the part 8, after the same has been assembled in the pad 1, a cover plate 12 which may be of zylonite cemented, or pressed with heat into place, or if preferred, it may be of any other suitable non-metallic material. The cover plate 12

is here shown as being depressed beneath the rear face of pad 1, but it may be, and perhaps preferably should be, flush with such rear face.

Any suitable means may be provided for securing the pad 1 to the spectacle frame, and for that purpose there is provided beneath the bridge 4 and extending inwardly from the rims 2, short ductile rods 13.

Rods 13 carry on their ends a buckle 14. The buckle 14 is approximately square in form and has a tongue or tang 15 extending partially across the same.

The tubular portion 7 of member 6 is of the proper size to be positioned in the buckle 14, and this is accomplished by bending the frame or boxlike portion of the buckle out of line with the tang so that the latter may be inserted into the tubular part 7, whereupon the frame is bent toward the pad to surround the journal bearing 7 and prevent separation of the parts while in that relative position. This particular connection forms no portion of the present invention.

It will be understood that a pad 1 is ordinarily assembled on both of the rods 13 which extend inwardly from the rims 2.

I have here shown the pad 1 as applied to what is commonly known as a spectacle frame, but it will be understood that such pad may be used on other types of frames such as those commonly known as pince-nez, or others.

It will also be understood that although I have mentioned several materials which may suitably be used in making my improved pad, numerous others may be found to be appropriate for such use, and although I have shown and described a specific structure and form and relation of parts as an exemplification or an embodiment of my invention, I do not desire to restrict myself to the details of size, shape or arrangement of parts, or to the exact method here shown of moving the parts into their final relationship, as various changes may be made within the scope of the appended claims.

I claim:

1. An ophthalmic pad comprising a main body portion having a recess in one face, the bottom of said recess being greater in area than the upper end thereof, a member seated on the bottom of the recess, said member being greater in area than the area of the upper end of the recess, a non-metallic covering overlying the outer face of said member, and means on the member for attaching the pad to an eye-glass frame.

2. An ophthalmic pad comprising a main body portion having a recess in one face, the bottom of said recess being greater in area than the upper end thereof, a metallic member seated on the bottom of the recess, said metallic member being greater in area than the area of the upper end of the recess, a non-metallic covering overlying the outer face of said metallic member, and means on the metallic member for attaching the pad to an eye-glass frame.

3. An ophthalmic pad comprising a main body portion having a recess in one face, the bottom of said recess being greater in area than the upper end thereof, a member seated on the bottom of the recess, said member being greater in area than the area of the upper end of the recess, a non-metallic covering overlying the outer face of

said member, and a ring on the member for attaching the pad to an eye-glass frame.

4. An ophthalmic pad comprising a main body portion having a recess in one face, the bottom of said recess being greater in area than the upper end thereof, a metallic member seated on the bottom of the recess, said metallic member being greater in area than the area of the upper end of the recess, a non-metallic covering overlying the outer face of said metallic member, and a ring on the metallic member for attaching the pad to an eye-glass frame.

5. In a spectacle or eye-glass frame, a nose pad comprising a non-metallic body portion having a recess in the rear surface thereof provided with a substantially flat bottom wall and inwardly inclined side walls, a bendable metallic member seated in the recess with its edge underlying the inwardly inclined side walls, a journal rigidly connected to said member, and a non-metallic disk secured upon and covering the outer surface of said member.

6. In a spectacle or eye-glass frame, a nose pad comprising a non-metallic body portion having a recess in the rear surface thereof provided with overhanging walls, a bendable metallic member seated in the recess with its edges underlying the overhanging walls, a journal rigidly connected to said member, and a non-metallic disk secured upon and covering the outer surface of said member.

7. In a spectacle or eye-glass frame, a nose pad comprising a non-metallic body portion having a recess in the rear surface thereof provided with a substantially flat bottom wall and inwardly inclined side walls, a bendable metallic member seated in the recess with its edge underlying the inwardly inclined side walls, a journal rigidly connected to said member, and a non-metallic disk secured upon and covering the outer surface of said member.

8. The method of producing an ophthalmic pad structure comprising forming a recess in the rear face of a self-sustaining body portion extending partially through the body with the opening leading to the recess of less area than the bottom of the recess to provide side walls overhanging said base, shaping a bendable concavo-convex metallic member of a size capable of passing through the opening leading to the recess and provided with a journal thereon, inserting said member through said opening into said recess and then deforming said member by pressure to expand its edges underneath said overhanging walls to secure the body and member together.

9. The method of producing an ophthalmic pad structure comprising forming a recess in the rear face of a self-sustaining body portion extending partially through the body with the opening leading to the recess of less area than the bottom of the recess to provide side walls overhanging said base, shaping a bendable concavo-convex metallic member of a size capable of passing through the opening leading to the recess and provided with a journal thereon, inserting said member through said opening into said recess and then deforming said member by pressure to expand its edges underneath said overhanging walls to secure the body and member together, and then securing a non-metallic covering over the outer face of said metallic member.
